UNITED STATES PATENT OFFICE.

ELAM A. OLIVER, OF BELLEVILLE, WISCONSIN.

BOLT-MAKING DEVICE.

SPECIFICATION forming part of Letters Patent No. 311,083, dated January 20, 1885.

Application filed March 26, 1884. (No model.)

To all whom it may concern:

Be it known that I, ELAM A. OLIVER, of Belleville, county of Dane and State of Wisconsin, have invented a new and useful Improvement in Vises and Shears; and I do hereby declare that the following is a full, clear, and exact description of the invention, which will enable others skilled in the art to which it appertains, to make and use it, reference being had to the accompanying drawings, forming a part thereof.

My invention relates to improvements in mechanics' vises in which a vise and shears operate in conjunction; and the objects of my invention are, first, to obtain a perfect closure of the jaws of the vise; second, to provide cutting apparatus to operate in unison with the vise; third, to magnify the power exerted to close the jaws of the vise; and, fourth, to obtain compactness of form. I attain these objects by the means shown in the accompanying drawings, in which—

Figure 1 is a side elevation of my invention ready for use. Fig. 2 is a plan view of my invention when in use. Fig. 3 is a front elevation of Fig. 1. Fig. 4 is a detail of shears and guide.

The device is formed with one stationary limb, N, fixed to the floor or other part by the foot O and braces P P, as shown, and a pivoted limb, H, secured by the pivot J to bracket T, which is formed or fixed upon the stationary limb N. Each of the limbs carries a jaw, the one upon limb N being marked M, and that upon limb H being marked K. Each limb also carries a shear-blade on one side, as shown, that upon limb N being marked R, and that upon limb H being marked R'. The limb H is operated, by mechanism hereinafter explained, to approach and recede from limb N at the top, so as to close and open the jaws and blades.

Upon the stationary limb N is secured an arm, S, which projects toward the limb H on the side opposite to the shear-blades, and serves to prevent the metal being cut from twisting, said metal to be cut being placed between the limb N and the arm S, between the shear-blades, as may readily be understood from Fig. 1. The lower end of the arm S is turned outward toward the limb H to form a guide, S', therefor. This guide S', lying snugly up

against the limb H, serves to keep it from twisting or moving upon its pivot J to any great or hurtful degree. The pivoted limb H 55 is provided with the longitudinal slot G, and is operated by the following mechanism: A curved foot-lever, A, is fulcrumed on the pivot B to the parts D D, and has a flange or flanges, C, which rest under the parts D, below the 60 pivot B, and afford a means for engaging the lever A and parts D rigidly when the lever is depressed, and at the same time allow the lever A to be elevated by being turned upward on its pivot B, when desired. The parts D are 65 fulcrumed upon the pivot E, supported by limb N. At their lower ends the parts D are provided with a friction-roller, F, which works in the slot G in the limb H. Now, it is evident that as lever A is depressed the lower 70 end of the pivoted limb H will be forced away from the limb N, and the jaw K and blade R' thrown toward jaw M and blade R, and that they remain so as long as power is applied to lever A. If the weight of the limb H below 75 the pivot J, united with that of the parts D below the pivot E, exceed that of these parts D H above said pivots united with that of lever A, the jaw K will be automatically thrown back or opened when the power is removed from lever A; but as this would unnecessarily increase the weight and cost of these parts an automatic means is provided for opening the jaws when the power is removed from the lever A. This consists of a 80 spring, I, wound round pivot E, and secured at one end to a brace, P, and having an outward-extending limb or end which engages with a loop, F², extending out from the roller F. The force of this spring tends to keep 85 the jaws open, and although readily overcome when power is applied to the lever A, yet its force is sufficient to make the opening of the jaws decided and immediate when the power is removed from lever A. The jaws K and 90 M are provided with grooves LL, which match each other in the two jaws, and form circular openings between them for holding circular objects.

My invention is designed, principally, for the 100 manufacture of bolts, to do which the operation is as follows: The iron bars are cut in lengths longer than is requisite by means of the shears R R'. These cut bars are taken and

put into the grooves L L in the vise hot, where they are held firmly and then headed. In the cutting the bar is kept from twisting by the guide S, which forms an acute angle with the inner side of the arm N, the opening of the angle being at the top, thus holding any-sized bar. When the foot is raised off the lever A, the spring I, by means of its engagement with the loop F', forces the lever D down, and the lower part of the arm H in, thereby opening the jaws of the vise. The lever A is jointed to the parts D in order that when not in use it may be thrown up out of the way, as shown in dotted lines in Fig. 1.

15 Of course I do not confine myself to the manufacture of bolts, but claim all the purposes for which it may be used.

Having thus fully described my invention, what I claim, and desire to secure by Letters 20 Patent of the United States, is—

1. The combination, with the stationary limb N and pivoted limb H, of the parts D, connected with the limb H, as described, and the lever A, pivoted to parts D, and provided with 25 the locking-flange C, as set forth.

2. The combination, with the upright limbs

N and H, having the jaws K and M and the shears R' and R, of a guide placed upon one limb, having a lower horizontal portion, S', serving as guide for the other limb, and an 30 upright portion, S, extending up beside the shears, to prevent twisting of the metal being cut, as set forth.

3. The combination of the lever A and parts D, provided with the anti-friction-roller F, 35 with fixed limb N, and the pivoted limb H, provided with the slot G in its lower end, in which the roller F works, and the jaws K and M, substantially as set forth.

4. The combination, with the levers A and 40 D, fixed limb N, and the pivoted limb H, of the spring I and jaws K and M, said spring being secured to a fixed part at one end and to the pivot of parts D and H at the other, as set forth. 45

In testimony that I claim the foregoing I append my signature.

ELAM A. OLIVER.
